CLAIM

We claim the ornamental design for a vehicular rear door interior with rear quarter trim, as shown and described.

DESCRIPTION

FIG. 1 is a front perspective view showing a vehicular rear door interior with rear quarter trim of our new design; FIG. 2 is a top plan view showing the vehicular rear door interior with rear quarter trim of our new design; FIG. 3 is a front plan view showing the vehicular rear door interior with rear quarter trim of our new design; and, FIG. 4 is a side plan view showing the vehicular rear door interior with rear quarter trim of our new design.

The stipple pattern on first portions of the vehicular rear door interior with rear quarter trim indicates a contrast in appearance from second portions thereof without stippling. The broken lines (for example, seats, front portion of a door armrest, and a window frame) in the drawings are for the purpose of illustrating environmental structure and form no part of the claimed design.
